UNITED STATES PATENT OFFICE

130,434

DESIGN FOR AN EXTENSIBLE AERIAL HEAD

Cary W. Martin, Los Angeles, Calif.

Application March 8, 1940, Serial No. 90,776

Term of patent 14 years

To all whom it may concern:

Be it known that I, Cary W. Martin, a citizen of the United States, residing in Los Angeles, in the county of Los Angeles and State of California, have invented a new, original, and ornamental Design for an Extensible Aerial Head, of which the following is a specification, reference being had to the accompanying drawing, forming a part thereof.

Figure 1 is a side elevational view of an extensible aerial head incorporating the invention.

Figure 2 is a top plan view of the same.

I claim:

The ornamental design for an extensible aerial head, substantially as shown.

CARY W. MARTIN.
